MASS SPECTROMETRY

Charles F. Robinson, Pasadena, Calif., assignor, by mesne assignments, to Consolidated Electrodynamics Corporation, Pasadena, Calif., a corporation of California

Application May 18, 1955, Serial No. 509,141

5 Claims. (Cl. 250—41.9)

This invention is concerned with mass spectrometers. It provides improvements for protecting an ion beam to be analyzed from the effects of static charges built up within the spectrometer so that the calibration remains unchanged over longer periods and the accuracy of analysis is improved.

A mass spectrometer is essentially an apparatus for producing ions and sorting them according to the ratio of their mass to their charge, i. e. according to their specific mass. A sample to be analyzed, such as a gas mixture, is ionized, usually by electron bombardment, and the resulting ions are propelled by an electrical potential into an analyzer. The ions enter the analyzer as an unscattered beam, and in the analyzer are sorted under the influence of an electromagnetic or electrical field, or both, into a series of divergent homogeneous beams of ions having the same specific mass. The sorted ions are collected and discharged, the quantity of each kind of ions being measured by the amount of current that they discharge upon collection.

In some types of mass spectrometer the ions have an energy in the order of 10 volts so that any static charges built up on the inner surfaces of the analyzer chamber will seriously impair resolution of the instrument if focusing makes use of an electrical field.

In the type of mass spectrometer to which this invention is directed primarily, ionization of the molecules is accomplished in an ionization chamber, or ion source, by bombardment with an electron beam. The resulting ions diffuse or are propelled into the analyzer chamber and are sorted under the influence of crossed magnetic and electric fields, which cause the ion beams to travel in characteristic cycloidal paths. Such a path is that traced by a point on a radius of a circle rolling in a plane along a line in the plane, which in this instance is a plane perpendicular to the magnetic field, and may also be considered as being rigorously circular in a coordinate system moving with uniform velocity. The velocity of the coordinate system or the center of the rolling circle is solely a function of the ratio of the electric and magnetic field strengths.

From the periodic property of the cycloid a charged particle which is introduced into transverse magnetic and electrical fields and which crosses a plane normal to the electric field will again cross this same plane when the particle is going in the same direction of travel at a distance proportional to its mass-to-charge ratio. And if the electrical field strength is uniform so that the coordinate systems or centers of the rolling circles corresponding to each ion move at the same velocity, ions of a particular mass will converge to a series of identical focal points after any whole number of turns in the magnetic field regardless of their velocity or direction of travel at the moment of introduction into the field.

In a typical instrument of this type the electrical field is established in the space defined by the analyzer body by a plurality of spaced, parallel electrodes, with one of the electrodes defining a so-called focal plane and two

of the electrodes, often called field electrodes, defining opposite interior surfaces of the analyzer body. Ions are introduced through an inlet aperture located in the focal plane defining electrode and are focused through a resolving aperture in the electrode at a given distance from the inlet aperture. These slit positions are normally fixed with respect to each other; the distance between them is the focal distance. Under such circumstances the focal distance X_f in centimeters is given by

10 the expression

$$X_f = \frac{2\pi m E c^2}{q B^2}$$

where

15 B =the magnetic field strength in Gauss;
 E =the electrical field strength in statvolt/cm.;
 q =the ion charge in e. s. u.;
 m =the ion mass in grams; and
 c =the speed of light in cm./sec.

20 Since in practice the focal distance X_f is fixed, the ion mass m is determined by calculation from ascertained values of the electric field strength E and the magnetic field strength B . It is thus of utmost importance that the electric field strength be accurately ascertained and that uniformity be maintained to the greatest extent possible.

25 However, it has been found that some of the ions formed in a cross-field mass spectrometer tend to lodge upon the electrodes used to produce the electric field in the mass spectrometer and to build up static charges on the surfaces of these electrodes. When an ion beam strikes a surface at near-grazing incidence, the surface tends to acquire a localized charge such that the electric potential of the surface is different from the potential of the underlying metal. The surface potential may thus be different from the potential of the underlying metal by as much as 70 volts.

30 In a conventional mass spectrometer the ion beam does not strike a surface at near-grazing incidence except when the beam has a very substantial amount of energy, of the order of several hundred or a few thousand volts, and such surface charges have a comparatively small effect if good cleaning methods are used on the surfaces. However, in instruments such as cycloidal mass spectrometers in which the dependence of focal distance on the ion energy is reduced or eliminated, an electrical field must be provided, usually by a plurality of electrodes. And since two of such electrodes in practice form the opposite inner surfaces of the analyzer chamber body, it is inherent that if the required electrical field is obtained by electrodes heretofore existing in the art, grazing incidence of ions will occur and the resolution will be impaired seriously by the resultant build-up 35 of surface charges, causing nonuniformity in the electric field and creating potentials of unknown values.

35 The first order effect of nonuniformity in the electrical field is not to destroy the quality of the focus but to displace the position in which this focus occurs, compared 40 to an instrument in which a collector electrode is located at the proper point of focus based upon consideration of uniform electrical and magnetic fields. In the event the point of focus is displaced as a result of any non-uniformity of the electrical field, resolution is impaired 45 since the focal point no longer coincides with the resolving slit.

45 The magnitude of the effect can be much reduced by careful cleaning procedures. But even if the cleaning has been thorough at the outset, the surfaces will become 50 contaminated through use and the effect will make its appearance in a short time which may be from a few hours to a few weeks depending on the initial condition

of the surface. It is also possible to alleviate the effects of surface charges or polarization by using a very large electrode structure so that the surfaces which exhibit polarization are far removed from the ion beam of interest. This causes the unit to become much bulkier and more expensive than necessary.

I have now developed a means which mitigates the effects of surface charges on the field electrodes, and which possesses distinct advantages over previously suggested methods. This objective can be accomplished by arranging the unit so that a given field electrode appears to define a plane as far as the electrical field configuration is concerned. However, that part of the electrode in which grazing incidence of ions will occur is actually a series of louvers such as the slats of a Venetian blind. The louvers are inclined so that an ion striking the electrode will strike a louver surface facing away from the ion beam and thus the ion beam of interest will be shielded from the resulting surface charge. Such an arrangement alleviates the effects of surface charge by permitting them to build up only in locations where they do no harm. Moreover, since the louvers may be constructed so that the space between them is opened through the thickness of the electrode, the electrode structure which I have developed has the additional advantage of increasing pumping speed which further reduces the tendency for surface deposits to form.

The invention will be more clearly understood by reference to the accompanying drawings, in which:

Fig. 1 is a schematic sectional elevation of a cycloidal mass spectrometer in accordance with a particular adaptation of the invention;

Fig. 2 is a schematic sectional elevation taken along lines 2—2 of Fig. 1 in enlarged scale showing the plan view of the louvers in the electrodes;

Fig. 3 is a schematic sectional elevation of a conventional cross-field mass spectrometer showing the effect of static charges upon the ion beam; and

Fig. 4 is a schematic diagram showing the electrical circuitry of the mass spectrometer of Fig. 1.

The mass spectrometer shown in Fig. 1 comprises an envelope 10 having the usual connection 11 to a vacuum system (not shown) and sample inlet line 12. A series of electrodes 13, 14, 15, 16, 17, 18 are supported in the envelope in parallel, uniformly spaced relation. Electrode 16 defines a so-called focal plane and is provided with an ion inlet aperture 19 and a resolving aperture 20. Additionally, electrode 16 has relatively large openings 21, 22 to permit ion travel in a cycloidal trajectory.

Electrodes 13, 14, 15, 16, 17 and 18 are connected to a voltage divider 23 across which a voltage is applied from a variable source 24. By means of the electrodes and the divider network illustrated schematically, a uniform electrical field is applied across the region defined by the electrodes. The envelope is subjected to a magnetic field developed by magnet poles, one of which is shown as the circular pole 25. The direction of the magnetic field is normal to the uniform electrical field.

An ion source 26 is disposed adjacent the ion entry slit aperture 19 in electrode 16. Shown schematically in Fig. 4, the ion source is in conventional form, including a repeller electrode 27, an accelerating electrode 28, an electron gun 29 and an electron target 30. By means of the electron gun and target an ionizing electron beam is directed across the ion source. The repeller electrode 27 and accelerating electrode 28 are connected to a voltage divider network 31 which is in turn connected across the voltage source 24. Electron gun 29 is connected through a transformer 32 to an A. C. source 33 for filament heat and through a bias battery 34 to the accelerator 28. The target 30 is connected through a bias battery 35 to the accelerator 28.

A sample to be analyzed is introduced through inlet 12 which is directly connected into the ion source 26. Under influence of the ionizing electron beam the sam-

ple is ionized. Ions from the source pass through the inlet aperture 19 and into the analyzer chamber 42 by the action of an accelerating potential existing between the repeller electrode 27, accelerating electrode 28 and plate electrode 16.

In an aperture in the middle portion of the electrode 13 thin louvers 38 are placed and conductively attached to electrode 13. The louvers as shown are parallel, uniformly spaced and inclined into the direction of travel of ions under the influence of the crossed magnetic and electric fields. The center portion of electrode 18 is likewise provided with louvers 39 inclined into the path of the ions.

Use of a mass spectrometer constructed in conventional form, as shown in Fig. 3, causes static charges to be built up on the inner surfaces of the analyzer chamber body when ions, as shown, strike such surfaces at grazing incidence. Such ions will be heavy ions not in focus or stray ions from the focussed beam. Such surface charges create an unknown potential within the instrument and impair resolution by destroying uniformity of the electric field.

By contrast, the structure of my invention nullifies such surface charges, thereby greatly improving the accuracy and resolution of the instrument. In the preferred form of my invention which I have here described, the construction of the electrodes is such that a stray or heavy ion, as shown by the dotted line in Fig. 1, will strike the outward facing surface of a louver so that any resulting static electric charge on the surface of the electrode is shielded from the focused ion beam shown by the solid line in Fig. 1. Thus, surface static charges built up by stray ions striking an electrode will have little or no effect on the ion beam of interest.

As will be noted, an additional feature of my invention is that it provides means for increasing pumping speed. The top cover 40 and the bottom cover 41 which are placed adjacent the louvered field electrodes are provided with conduits 43 and 44 which lead through the connector 11 to vacuum pumps not shown. The louvered electrodes provide additional conduits between the analyzer chamber and the vacuum pumps, thereby increasing pumping speed and the efficiency of operation of the instrument.

I claim:

1. In a crossed-field mass spectrometer, the combination comprising an analyzer chamber body having an inner surface which defines an analyzer chamber, a source for producing ions connected to the analyzer chamber body, means propelling a beam of ions into the analyzer chamber, means establishing a magnetic field in a given direction in said analyzer chamber, means establishing an electric field transverse of said magnetic field within said analyzer chamber, said electric and magnetic fields being adapted to cause said ion beam to travel in a cycloidal trajectory to arrive at a point where the beam of ions of a predetermined mass is focussed, and louvers affixed to the inner surface of the analyzer chamber body to shield the trajectory of the focussed ion beam from electrostatic surface charges on said inner surface.

2. Apparatus in accordance with claim 1 in which the louvers are conductively connected to the analyzer chamber body.

3. In a crossed-field mass spectrometer, the combination comprising an analyzer chamber body which defines an analyzer chamber, means connected to the analyzer chamber body for producing ions and propelling ions into the analyzer chamber, a plurality of parallel electrodes for establishing an electric field in a given direction within the body, two of said electrodes being adapted to form opposite inner surfaces of the analyzer chamber body, means establishing a magnetic field transverse of said electric field within the analyzer chamber, said electric and magnetic fields being adapted to cause a beam of ions of a predetermined mass to travel in a

cycloidal trajectory to arrive at a point where the beam is focussed, and a series of louvers conductively attached to the inner surfaces of said two electrodes to shield the beam of ions of predetermined mass from surface charges on said electrodes caused by grazing incidence of ions other than those of said predetermined mass.

4. Apparatus in accordance with claim 3 in which the louvers are conductively attached in a parallel spaced relation in apertures in said two electrodes.

5. In a mass spectrometer, the combination comprising an analyzer chamber body which defines an analyzer chamber, a source for producing ions connected to the analyzer chamber body, means for propelling an ion

beam into the analyzer chamber, means disposed about the analyzer chamber for imparting a given trajectory within the analyzer chamber to a beam of ions of predetermined mass, and means conductively attached to the inner surface of the analyzer chamber body to shield said ion beam from electrostatic surface charges on said inner surface.
